UNITED STATES PATENT OFFICE.

WALTER D. BROWN, OF OAK PARK, ILLINOIS.

HAIR CURLER.

Application filed March 10, 1924. Serial No. 698,005.

To all whom it may concern:

Be it known that I, WALTER D. BROWN, a citizen of the United States, and a resident of Oak Park, in the county of Cook 5 and State of Illinois, have invented certain new and useful Improvements in Hair Curlers, of which the following is a specification.

My invention relates to hair curlers which 10 are particularly useful for curling bobbed hair. In general my improved hair curler comprises a clamping member which receives and clamps the bobbed hair at its ends and which is then turned on a longitudinal 15 axis to roll or wind up the hair to form the curl, a locking frame being provided which will serve as a handle for revolving the clamping member and which after rolling up of the hair can be secured 20 in place on the clamping member to lock the hair and clamping member against unrolling, so that the rolled up hair will be held in rolled up position until it is desired to release it. The object of the invention 25 is to produce a device of this class of simple inexpensive construction which can be readily and conveniently manipulated to roll up the hair and lock it, and which can be readily manipulated with one hand to be 30 unlocked and quickly released from the hair.

My improved device is clearly shown on the accompanying drawing, in which—

Fig. 1 is a plan view showing the device 35 clamped and locked,

Fig. 2 is a side elevational view thereof,

Fig. 3 shows the device open, ready to receive the ends of the hair to be curled,

Fig. 4 is a side elevational view showing 40 the clamping member about to be closed,

Fig. 5 is a plan view showing a modified construction,

Fig. 6 is an end view of the structure of Fig. 1 with the outer loop of the locking 45 frame broken away,

Fig. 7 is a plan view showing another modified construction and arrangement, and

Fig. 8 is a side view of the upper end of the clamping member of the structure of 50 Fig. 7.

Referring to the drawings the device comprises the clamping and curling member C and the locking member or frame L. The clamping member consists of a narrow strip 55 of spring steel folded substantially midway between its ends to form the clamping jaws

10 and 11. The end of the jaw 10 is bent back to form the locking hook 12 and the end 11' of the jaw 11 is tapered to engage below the hook 12 and to be locked in position by the corners 13 and 14 formed by the notch 15 in the hooked end. When the clamping member is open the spring effect of the metal will hold the jaws 10 and 11 spread apart as shown in Fig. 3, and the jaws are in a common plane. When the clamping member is to be closed the jaws are brought together and the jaw 11 is swung a distance laterally to bring its end 11' clear of the hook 12, whereupon the jaw 11 is then shifted into normal parallelism 60 with the jaw 10 with its end 11' under the hook 12 and locked by the corners 13 and 14. Before the clamping member is closed the ends of the bobbed hair to be curled are 65 inserted between the jaws and then the clamping member is rotated on its longitudinal axis to wind up the clamped hair thereon to form the curl. Provision must however be made to prevent unwinding or 70 unrolling of the hair and I provide the locking frame L. As shown this frame is 75 preferably constructed of wire bent to the desired shape. In Figs. 1 to 4 the frame is of oblong shape, and has the loops 16 and 17 at its inner and outer ends respectively. The loop 16 has its yoke 18 extending 80 through the holes 19 in the opposed walls of the bend 20 of the clamping member, so that the locking frame is hinged to the 85 clamping member. The loop 17 is adapted 90 to engage over the hooked end or crown of the jaw 10 where a transverse notch 21 is provided for receiving the loop yoke. The sides 22 and 23 of the locking frame 95 are deflected laterally to be spaced a distance away from the clamping member when the device is closed. The dimensions of the frame are such that the spring of the frame will hold the loop 17 within the locking 100 notch 21. Preferably the sides 22 and 23 are bowed slightly outwardly so that a slight pressure thereon will sufficiently elongate the frame L to permit the loop 17 to be readily brought over the crown end of 105 the jaw 10 and into the notch 21. Then when it is desired to unlatch the locking frame a slight pressure will withdraw the loop 17 from the locking notch to permit the frame to be readily swung into open 110 position. The ends of the wire forming the frame L may be secured together in any

desired manner as by soldering, riveting, welding, or otherwise. In Figs. 1 to 4, the joint 24 between the wire ends is in the side 23 and the joint is preferably formed 5 by spot welding the wire ends together.

When the curling device is open in the position shown in Fig. 3 the locking frame L will serve also as a handle, by which the clamping members after receiving and 10 clamping the hair may be readily rotated to roll up the hair thereon. After rolling up the hair the locking frame is swung into locking position with its loop 17 in the locking notch 21, and unwinding of the clamping 15 member is then prevented until the frame L is again unlocked. The edges e of the hook crown may be rounded as indicated so that the locking frame loop 17 may be readily brought into the notch 21. When 20 it is desired to undo the curling devices a slight pressure on the locking frame will then release the loop from the locking member and the frames can then be swung open and the clamping members unwound and 25 opened to release the curled hair. Opening of the clamping member is readily accomplished by a slight pressure and lateral shift of the end 11' of the jaw 11 to clear such end from the corners 13 and 14 and the hook 12. 30 In the arrangement of Fig. 5 the frame L is also formed of a single piece of wire, but the ends 25 and 26 instead of being welded together at the sides of the frame are hooked through the opening 19 to form the hinge 35 connection between the frame and the clamping member C.

In the arrangement of Fig. 7 the ends of the wire locking frame 27 and 28 are secured to a hinge pin or rivet 29 which extends 40 through the bend 20 of the clamping member C, thus to form a hinge connection between the frame and member. By distorting the frame L or by inclining the hinge pin 29 a trifle as indicated in Fig. 7 the 45 locking loop 30 of the frame will be slightly to one side of the hook 12 and must be swung laterally a distance in order to be brought around such hook. In the back of the hook is provided the locking notch 31 which receives the corresponding side 17' of the loop 17 to lock the frame to the clamping member, the loop being retained in the locking notch by the spring effect of the frame after such frame has been swung to fully closed 50 position as indicated in Fig. 7 where the dotted line shows the frame just before it is swung laterally into locking engagement with the notch 31. After clamping of the hair in the clamping member and rolling it

up, the locking frame is swung into parallelism with the clamping member and then a slight swing will bring it into locking engagement with the clamping member. A slight lateral swing will then again release it. 60

I thus produce a very simple, inexpensive and neat curling device which can be efficiently and easily manipulated to curl up bobbed hair and which will hold itself in locked position. 65

I do not desire to be limited to the exact construction, arrangement and operation shown and described, as changes are possible which will still come within the scope of the invention. 70

I claim as follows:

1. In a hair curling device of the class described, the combination of a clamping member comprising spring jaws secured together at one end and adapted to be brought together to receive hair to be curled, a locking hook at the end of one of said jaw members adapted to receive the other jaw member whereby said jaw members may be locked together to form a support on which the clamped hair may be wound up into a curl, a locking frame of spring metal hinged at one end to the joined end of said jaw members and being adapted to be swung into position to receive said clamping member and the hair wound up thereon to prevent unwinding of the hair, the hook at the end of one of said jaw members having a latch notch and said locking frame being adapted to spring into said notch to be thereby locked to the clamping member. 80 90 95

2. In a hair curling device of the class described, the combination of a clamping member formed of a band of spring metal bent intermediate its ends to provide opposed jaw members between which the ends of hair to be curled may be clamped, means for locking the ends of said jaw members together to clamp the received hair, said jaw members when locked together forming a support on which the clamped hair may be wound up to form a curl, a locking frame of spring wire hinged at one end to the bend of said clamping member, one of said jaw members having a latch notch, said locking frame being adapted to be swung into position with its free end in spring latching engagement in said notch to be thereby locked to the clamping member and to prevent unwinding of the hair thereon. 100 110 115

In witness whereof, I hereunto subscribe my name this 7th day of March, A. D. 1923.

WALTER D. BROWN.
